UNITED STATES PATENT OFFICE.

INGOMAR F. ORTON, OF GALVESTON, TEXAS.

WEED-KILLING CAR.

1,098,964.

Specification of Letters Patent. Patented June 2, 1914.

Application filed February 7, 1914. Serial No. 817,374.

To all whom it may concern:

Be it known that I, INGOMAR F. ORTON, a citizen of the United States, residing at Galveston, in the county of Galveston and State of Texas, have invented new and useful Improvements in Weed-Killing Cars, of which the following is a specification.

This invention relates to a weed killing car, of portable apparatus adapted to run upon a railway track for holding and distributing a weed killing solution, by which weeds and other growing vegetation along the line of the track may be destroyed.

One object of the invention is to provide a car including a storage tank to hold the liquid, combined with means for spraying the liquid along the line of the track, and means for controlling the supply of the liquid to the spraying device.

A further object of the invention is to provide a tank car for the purpose described which may be coupled to a locomotive or any car of a train and employed to distribute the solution along the trackway during the running of the train.

A still further object of the invention is to provide a car of the character described which is provided with a running board and hand rail, serving also as a guard rail, whereby the attendants in charge of the car may work with safety, together with means easily accessible from the running board for letting on or cutting off the flow of the liquid and regulating its flow as desired.

A still further object of the invention is to provide a car having a spray pipe which may be extended transversely across the trackway and beyond the line of the rails to distribute the solution over a wide area, and which may be turned when required to a position beneath and parallel with the car so as to avoid cattle guards, depot platforms, etc.

A still further object of the invention is to provide means whereby air from a storage tank on the car or from the air brake system of the car or another car may be employed to discharge or jet the solution through the spray pipe with the desired force.

The invention consists of the features of construction, combination and arrangement of parts herein fully described and claimed, reference being had to the accompanying drawings in which:

Figure 1 is a side elevation of a car of the

character described embodying my invention. Fig. 2 is a top plan view of the same. Fig. 3 is a bottom plan view of the car, with the trucks removed. Fig. 4 is a front elevation of the car. Fig. 5 is a vertical transverse section on the line 5—5 of Fig. 1. Fig. 6 is an enlarged detail section through the spray pipe. Fig. 7 is a detail view showing a mode of connecting the air supply pipes on the tank car with the air brake system of another car coupled thereto.

In carrying my invention into practice, I provide a suitable base frame 1, constructed of metal, wood or a combination of such materials, and mounted upon wheeled trucks 2 of the ordinary or any preferred construction for travel along the rails 3 of a railway track. The frame carries the usual end couplings 4 for connecting the car with a locomotive or any other car of a train, by which it may be drawn along the track when in service, and if desired the car may be provided with the usual hand brake and air brake mechanism.

Mounted upon the base frame 1 is a tank or reservoir 5 of any suitable capacity, designed to contain a desired supply of the weed killing solution or liquid. This solution may be supplied to the tank through a filling dome or inlet 6 normally closed by a suitable closure 8. The tank may be fixed at its bottom to the base frame in any preferred manner, and in addition I provide at intervals along the sides of the car supporting bracket rods or bars 9 fixed to the base frame and tank and serving as supports for a running board or platform 10 extending around the tank, the said rods or bars being connected at their upper ends by rods 11 forming a hand rail and also a guard rail extending up from the platform and around the top of the tank, allowing the attendant or attendants on the car to stand or move around with safety. Ladders 12 are provided at one or both sides of the car at the opposite ends thereof and are suspended from the running board or platform 10 and fastened at their lower ends by brackets 13 to the base frame, whereby they are rigidly supported in position. The tank is provided at its base, at or about centrally of its length with an outlet 14 for the discharge of the weed destroying liquid or solution, which outlet is governed by a cut off valve 15, by which the flow of liquid may be let on or cut off as desired. This valve is

connected to the lower end of a rod 16 extending upwardly through the dome 6 and connected at its upper end with a cam lever 17 whereby it may be conveniently raised or lowered in an obvious manner. The outlet is also controlled by a sliding regulating valve 18 by a crank arm 18' connected with a rod or shaft 19 journaled to oscillate in suitable bearings at one side of the car and extending 10 upwardly at one side of the tank in convenient position to the running board, the upper end of said rod being provided with a hand wheel or other operating device 20 whereby it may be turned or rotated to close 15 the valve or open it to any desired degree.

Communicating with the outlet below the valve is a distributor or spray pipe 21, preferably consisting of a series of connecting and perforated pipe sections, coupling 20 members and caps, the laterally extending arms of said spray pipe being intermediately joined by a central T-section 22 journaled upon the outlet so that the spray pipe may be disposed either transversely or longitudinally of the car. The pipe is of a length considerably greater than the width of the frame 1 or distance between the track rails 3, so that when extended laterally it will project across and beyond the track rails to a 30 desired extent, so that the discharging solution will be sprayed upon weeds or other plants growing between and outside of the track rails, whereby their destruction is effected. A chain or other suitable controlling device 23 leads from the hand rail at one side of the car downward to the spray pipe, by which said pipe may be swung transversely to working position or swung 35 inwardly beneath the car in a plane parallel therewith, to which latter position it is adjusted whenever necessary to avoid interference with cattle guards, depot platforms and other obstructions along the line of way.

It will be evident from the foregoing description that the flow of the solution may be let on or wholly cut off by means of the valve 15 and its discharge regulated as desired by means of the valve 18, which may also be adjusted to cut off the flow of the 50 solution whenever desired.

In practice, a chemical solution of proper character and strength to destroy refractory weeds, grasses and other growing vegetation is employed, and whenever necessary the 55 distributing car is coupled to another locomotive or to another car of a train for travel over a section of the railway infested with obnoxious weeds or plants, the solution being distributed along the track and spread 60 over the plants in the travel of the car, thus effecting a destruction of the growing plant life, by means of which the tracks of a railway may be kept clear of vegetation in a simple and economical manner. It is obvious 65 that the construction described allows

the apparatus to be readily and conveniently controlled without the necessity of employing a large number of attendants. The tank may be provided at each end with a drain valve 24 whereby the contents thereof may 70 be drawn off whenever desired.

It is desirable in some conditions to provide means by which the force of discharge of the solution may be increased, beyond that afforded by the force of gravity, and in 75 order to enable the solution to be discharged with any force desired I may provide means for supplying compressed air from a tank or reservoir on the distributing car itself, or for utilizing the air pressure from the air 80 brake system of a locomotive or adjoining car. To this end, air supply pipes 25 and 26 are provided upon the base frame 1 and beneath the reservoir tank, which pipes connect at their inner ends with the outlet 14 85 and extend therefrom on opposite sides of the longitudinal center of the car to the opposite ends of the car, where they may be connected with a suitable source of supply of air under pressure controlled in its supply 90 to the outlet in any preferred manner.

I claim:—

1. In an apparatus of the character described, the combination of a wheeled supporting frame, a reservoir carried thereby, 95 said reservoir being provided at its bottom with an outlet, a distributing pipe rotatably mounted upon the outlet and having laterally extending arms, said pipe being adapted for adjustment to a position beneath and 100 parallel with the reservoir and to a position at right angles thereto, and being of a length to extend laterally beyond the sides of the base when in the second named position, means for controlling the flow of liquid from 105 the reservoir through the outlet, and means for adjusting the distributor to either of the stated positions.

2. In an apparatus of the character described, the combination of a wheeled supporting frame, a reservoir carried by said frame and having in its bottom an outlet, a distributor rotatably mounted upon the outlet, said distributor comprising a central head and laterally extending perforated 115 pipes, said head and pipes being rotatable to positions parallel with and beneath the reservoir and at right angles to the reservoir, and being of a length to extend beyond the sides of the base frame when disposed in the 120 latter named position, a valve controlling the flow of liquid from the reservoir to the outlet, means extending parallel through the tank for operating said valve, a valve within the outlet for controlling the flow of the 125 liquid to the distributor, and controlling means adjustable from a side of the reservoir for controlling the latter named valve.

3. In an apparatus of the character described, the combination of a wheeled sup- 130

- porting frame, a reservoir carried thereby, an outlet depending centrally from the bottom of the reservoir, a distributor rotatably mounted upon said outlet, said distributor comprising a central head and perforated pipes extending laterally therefrom, said distributor being adjustable to extend longitudinally of and beneath the tank or at right angles thereto and being of a length 5 to extend laterally beyond the sides of the reservoir when adjusted to the latter named position, a valve controlling the flow of liquid from the reservoir to the outlet, a controlling device extending upwardly through 10 the tank and connected with said valve, a laterally sliding valve in the outlet for controlling the flow of the liquid therefrom to the distributor, said valve being provided with a crank arm, and a rod or shaft rotatably mounted at one side of the reservoir 15 and coupled to said crank arm for adjusting said sliding valve.
4. In an apparatus of the character described, the combination of a wheeled base frame, a liquid reservoir mounted thereon, an outlet depending from the bottom of the reservoir, a distributor rotatably mounted upon the outlet for adjustment to positions parallel with and beneath the reservoir and 20 at right angles thereto, and comprising a central head and laterally extending perforated pipes of a length to project beyond the sides of the base frame when adjusted to the second named position, a controlling valve 25 within the upper portion of the outlet for governing the flow of liquid from the reservoir thereto, a controlling valve within the lower portion of the outlet for controlling the flow of the liquid from the outlet to the 30 distributor, and air supply pipes extending longitudinally in opposite directions along the bottom of the reservoir and communicating at their inner ends with the outlet at a point between said valves.
- 45 5. An apparatus of the character described comprising a wheeled base frame, a reservoir tank mounted thereon and having a filling inlet at its top and a discharge outlet at its bottom, a valve controlling the flow of liquid from the tank to the outlet, a controlling device at the top of the tank for adjusting said valve, a valve controlling the flow of liquid through the outlet, a device at the side of the tank for adjusting said valve, and a distributing device communicating 50 with the outlet.
6. An apparatus of the character described comprising a wheeled base frame, a reservoir tank mounted on said base frame and provided at its top with a filling inlet and at 55 its bottom with a discharge outlet, and a cut off valve controlling said outlet, a rod extending upwardly through the tank and filling inlet and connected with said valve, an operating element connected with the rod 60 for adjusting the valve, and a regulating valve in the outlet, a controlling device at one side of the tank for adjusting said regulating valve, a spray pipe mounted upon the outlet for adjustment to positions transversely or longitudinally of the apparatus, and means for adjusting said spray pipe.
7. An apparatus of the character described comprising a wheeled base frame, a reservoir tank supported by said frame having a top 65 filling inlet and a bottom discharge outlet, uprights connected with the frame and tank, a running board supported by said uprights, a guard rail supported by the uprights at the top of the tank, a valve within the tank 70 controlling the flow of the liquid therefrom to the outlet, means extending to the top of the tank and exteriorly thereof for adjusting said valve, a controlling valve within the outlet, a device upon the exterior of the tank 75 and accessible from the running board for adjusting said valve, and a spray pipe connected with the outlet.
- In testimony whereof I affix my signature in presence of two witnesses.
